UNITED STATES PATENT OFFICE

152,279

DESIGN FOR A LIQUOR JIGGER OR SIMILAR ARTICLE

Thomas B. McKiernan, Meriden, Conn., assignor to The Ellmore Silver Co., Inc., Meriden, Conn., a corporation of Connecticut

Application May 14, 1947, Serial No. 139,032

Term of patent 14 years

(Cl. D36—8)

To all whom it may concern:

Be it known that I, Thomas B. McKiernan, a citizen of the United States, residing in the city of Meriden, county of New Haven and State of Connecticut, have invented a new, original, and ornamental Design for a Liquor Jigger or Similar Article, of which the following is a specification, reference being had to the accompanying drawing, forming a part thereof.

Fig. 1 is a side elevation of a liquor jigger or similar article, showing my new design, in position to receive liquid;

Fig. 2 is a front elevation in the upside down position; and

Fig. 3 is a top plan view thereof.

I claim:

The ornamental design for a liquor jigger or similar article, as shown.

THOMAS B. McKIERNAN.
